UNITED STATES PATENT OFFICE.

JOHN B. MORTON, JR., OF CHARLESTON, WEST VIRGINIA.

FLOOR-CLEANING MACHINE.

Application filed September 28, 1922. Serial No. 591,031.

To all whom it may concern:

Be it known that I, JOHN B. MORTON, Jr., a citizen of the United States, residing at Charleston, in the county of Kanawha and State of West Virginia, have invented new and useful Improvements in Floor-Cleaning Machines, of which the following is a specification.

The general object of my said invention is 10 the provision of a floor cleaning machine that is easy of operation, is efficient in practice, and is possessed of a wide range of utility.

To the attainment of the foregoing, the 15 invention consists in the improvement as hereinafter described and definitely claimed.

In the accompanying drawings, forming part of this specification:—

Figure 1 is a side elevation of the best 20 practical embodiment of my present invention that I have as yet devised.

Figure 2 is a plan view of the same.

Figure 3 is a longitudinal, vertical-central section of the machine.

25 Figure 4 is a transverse section taken in the plane indicated by the line 4—4 of Figure 3.

Figure 5 is a longitudinal, vertical section showing the machine equipped for use as a 30 vacuum cleaner.

Figure 6 is an elevation taken at right angles to Figure 5 and showing the major portion of the vacuum cleaner equipment.

Figures 7, 8, 9 and 10 are views of details hereinafter explicitly referred to.

Similar numerals of reference designate corresponding parts in all of the views of the drawings.

Included in the machine is a casing body 1 40 with side shaft projections 2 for the pivotal connection of the bail portion 3 of a handle 4 through which the machine can be conveniently moved over the surface to be cleaned.

The said casing body 1 is supported by 45 wheels 5 and contains in its lower rear portion a water tank 6, Figures 3, 4 and 5. In

the upper portion of the rear wall of the tank 6 is an opening above and partially about which is a cylindrical wall 7, carried

50 by and extending forwardly from the said rear wall. The forward portion 8 of the casing body 1 is preferably shaped as illustrated, and is open at its underside, Figures 3 and 5. Between the top wall 9 of the tank 6 and the top wall of the casing body 1

is a compartment 10, Figures 3 and 5, and permanently arranged in the said compartment 10 is an electric motor 11 with a spur gear 12, and a band pulley 13 on its armature shaft 14. Also located in the compartment 10 but at the opposite side, with reference to the band pulley 13, is a train of gearing 15; Figures 3 and 4, in connection with the spur gear 12. The motor 11 is designed to be electrically connected with an appropriate source of electric energy by wires 16, Figure 1, the handle 4 being preferably equipped with a switch (not shown) under the control of the operator of the machine after the manner disclosed in my contemporary application filed July 12, 1921, Serial No. 484,044.

In the upper forward portion of the tank 6 is a transverse trough 17, Figures 3-5, designed to contain water, and overhanging the forward portion of the said trough is a chute 18 connected to the front wall 19 of the tank 6 and arranged under and extending in rear of the opening 20 in the upper forward corner of the tank 6.

Arranged in the forward portion 8 of the casing body 1 is a frame that includes parallel side members 21, one of which is shown in Figure 3. In accordance with one part of my present invention the said frame 65 is detachably secured in the casing body portion 8, the means employed for said purpose being, by preference, screws 22, Figure 1, which extend through the side walls of the portion 8 and into threaded apertures 23, 80 Figure 3, in the member 21.

Carried in the lower portion of the frame including the side members 21 are forward and rear rollers 24 in the centers of which are circumferential grooves 25, Figures 3 95 and 7.

In the top wall of the casing body 1 are openings 26, one of which is shown in Figure 10. The said openings 26 receive the threaded shanks 27 of slotted hangers 28, 100 the said hangers serving to receive the journals 29 of an upper transverse roller 30 which is centrally grooved correspondingly to the lower rollers 24. Said roller 30 is equipped at one end with a spur gear 31 in connection with the before mentioned train of gears 15, and is also equipped at its ends with spur gears 32. These latter are intermeshed with corresponding gears 33 on the journals 34 of a lower expressing roller 35. 105 110

Said journals 34 are disposed in bearings 35' slideable in the hangers 28 and pressed upwardly by springs 36 so as to hold the roller 35 under yielding pressure against an endless mopping cloth or belt 37, Figures 1, 3 and 8. The said cloth or belt 37 is formed of appropriate mopping material, and is characterized by a longitudinal projection or rib 38 at its back, Figures 1, 3 and 8, the said rib being disposed and movable in the circumferential grooves of the rollers 24 and 30, and being designed and adapted to preclude sidewise creeping or casual movement of the belt relative to the several rollers.

15 On the shanks 27 of the hangers 28 are removable wing nuts 39 which bear on the casing body 1 and thereby support the hangers and the parts carried thereby.

By comparison of Figures 1, 2 and 3 it will be understood that the front of the casing body portion 8 is formed by a wall 40, hinged at 41 to the portion 42 of the cover 40* of the casing body. At its lower end the wall 40 is provided with forwardly-deflected side arms 43, and in the said side arms are journaled trunnions 44 at the ends of an open trough 45 on one end wall of which is an upstanding arm 46. Connected to and depending from the forward edge 30 of the trough 45 is a skirt 47 of flexible sheet rubber which is designed and adapted to cause water to flow cleanly immediately in front of the forward roller 24, and which when pushed against a wall will bend backwardly and thereby enable the mop cloth or belt 37 to rub and scrub a floor up to the wall.

The trough 45 is supplied with water from the tank 6 through the conduit or pipe shown in Figures 1 and 2. The said conduit or pipe comprises a horizontal portion 50 arranged at the height of the water in the tank 6 when the said tank is full. It also comprises a portion 51 that extends inwardly and downwardly within the tank 6, and a valved portion 52 that extends downwardly from the portion 50 and is arranged to discharge into the trough 45, Figure 1. The valve, designated by 53, may be of any construction compatible with the purpose 50 of my invention. It will be readily understood that when the tank 6 is filled with water above the level of the pipe portion 50, and the valve 53 is open, water will flow through the pipe into the trough 45, and this will continue due to siphonic action until the water in the tank 6 falls below the lower end of the pipe portion 52.

When the trough 45 is tilted to depress the forward edge thereof water will discharge from the said trough in a thin sheet. The trough discharge is also materially advantageous because there is no liability of its being impaired by sediment in the water as is the case with a pipe having minute discharge apertures. For the manipulation of

the trough 45 and the valve 53 through the medium of the hinged handle 4 I provide the means shown in Figures 1 and 2. The said means comprises a rock shaft 60 journaled in bearings 61 on the wall or member 70 40 and having cranks 62 and 63, a rod 64 connecting the crank 63 and the handle portion 3, a crank 65 on the stem of the valve 53 and connected by a rod 66 with the crank 62, and a rod 67 connecting the crank 65 and the arm 46 of the trough 45. When the handle 4 is slightly raised from the position shown in Figure 1, the valve 53 will be opened and the trough 45 will be tilted to depress the forward edge thereof and bring about the discharge of water therefrom in the manner before described, and when the handle is returned to the position shown the valve 53 will be closed and the trough 45 will be restored to the position 85 shown in Figure 1. Obviously when the operator tilts the cleaner so as to lift the mop cloth or belt from the floor, water collected in the trough 45 will be discharged from the rear edge of the trough to the 90 forward stretch of the mop cloth or belt and will be carried by the mop cloth or belt up to the wringing or pressing means which will bring about the return of such water to the tank 6. It will be noted by 95 reference to Figure 3 that water expressed from the mop cloth or belt by the rollers 30 and 35 will pass over the chute 18 to the trough 17. Dirt will sink to the bottom of the said trough while water will flow over the rear edge of the trough and return to the tank 6. Manifestly there is nothing about the trough 17 that is liable to become clogged, and when necessary dirt and other sediment collected in the trough 17 may be 100 readily removed therefrom. It will also be understood that water may be supplied to the tank 6 through the large opening in the rear wall thereof, and when desired water may be poured from the tank through 110 the said opening.

By reference to Figures 1 and 2, it will be observed that the forward portions of the casing body and the wall or member 40 are reduced in width as designated by 70, i. e., 115 are of a less width than the mop cloth or belt 37. In virtue of this provision one edge portion of the mop cloth or belt will act against the portion of a floor where the floor and wall join when the cleaner is moved along in slight angular relation closely adjacent said wall.

As best shown in Figure 4 my novel cleaner is equipped in addition to the usual side wheels 5 with a longitudinal center wheel 5*. This provision adapts the cleaner to be used with facility in the mopping of steps, the casing body 1 being moved in the direction of the length of the step being cleaned at which time the cleaner will be 120 125 130

supported by one of the side wheels 5 and the central wheel 5*, the other side wheel 5 being beyond the step and idle.

When the tank or reservoir 6 is supplied with floor oil my novel apparatus may be used to advantage to oil a floor, and when the cleaner is used in a dry state the cloth or belt 37 will serve to expeditiously and thoroughly polish a wax floor.

10 The frame members 21 and the hangers 28 together with the elements carried by said frame members and hangers are preferably removable from the forward portion of the casing body to give place to the 15 vacuum cleaning equipment shown in Figures 5 and 6. The said equipment comprises a fan casing 80, a rotary fan 81 therein, a discharge nozzle 82 on the fan casing and adapted to rest on the chute 18, Figure 5, 20 and a trunk 83 having an open lower end 84 and also having arms 85 communicating with the casing 80 at the ends thereof. The arms 85 are provided at 86 with closure members bearing gaskets 86* and adapted 25 to rest on the chute 18 and effectively close the portions of the before described opening 20 at opposite sides of the spout 82. The fan 81 is fixed on a shaft 87 and also fixed on the shaft 87 is a pulley 88, designed to be 30 connected by a belt 89 with the before mentioned pulley 13 on the armature shaft of the motor 11. It will also be noticed that the trunk 83 is provided at 90 with lugs to which are side plates 91 having threaded 35 apertures 92 to receive screws 22 by which the vacuum cleaning means can be detachably secured in the forward portion of the casing body 1.

When the vacuum cleaning attachment is 40 employed in the relation shown in the casing body 1, it will be apparent that the fan 81 can be rotated at a high rate of speed to assure dirt and dust being drawn from a carpet or floor rug and discharged into the 45 tank 6. I would also have it understood that when the vacuum cleaner attachment is used in the casing body 1, I employ in the cylindrical wall 7 of the large opening in the rear end of the casing body 1 means to permit 50 the escape of air from the tank 6 while trapping dust and dirt in the tank. The said air-straining means designated by 93 in Figure 9, is removable and may be of any appropriate construction without involving 55 departure from the scope of my claimed invention. I prefer, however, to have the said means 93 comprise three thicknesses of finely woven textile 94 and three rims 95 relatively arranged as shown and adapted 60 to maintain the straining diaphragms 94 in spaced relation in the cylindrical wall 7. When the apparatus is to be used for mopping and analogous purposes the straining means will of course be removed from the 65 cylindrical wall 7.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention 75 various changes and modifications may be made such as fall within the scope of my invention as defined in my appended claims.

Having described my invention, what I claim and desire to secure by Letters Patent, is:—

1. A floor cleaner of portable type comprising carrying means, a tank carried thereby, an endless mopping cloth or belt carried by the carrying means, means to drive said cloth or belt, means to supply water from the tank to a surface to be cleaned, side wheels supporting the carrying means, and an auxiliary wheel supporting the carrying means and arranged intermediate the side 90 wheels.

2. In a floor cleaner of portable type, the combination of carrying means, mopping means carried by the carrying means, a tank also carried by the carrying means, a trough 95 carried by the carrying means, and means for conducting fluid from the tank to said trough, said trough adapted to discharge water in a sheet from one of its edges and said trough being tiltable, and means under 100 the control of the operator for tilting the trough.

3. In a floor cleaner of portable type, the combination of carrying means, mopping means carried by the carrying means, a tank 105 also carried by the carrying means, a trough carried by the carrying means, and means for conducting fluid from the tank to said trough, said trough adapted to discharge water in a sheet from one of its edges, and said trough being tiltable, and said conducting means being equipped with a valve, in combination with means to enable an operator to synchronously tilt the trough and open the valve.

4. In a floor cleaner of portable type, the combination of carrying means, mopping means carried by the carrying means, a tank also carried by the carrying means, a trough carried by the carrying means, and means for conducting fluid from the tank to said trough, said trough adapted to discharge water in a sheet from one of its edges, the said trough being tiltable, in combination with a handle movable relative to the carrying means, and a connection between said movable handle and the trough to tilt the latter by movement of the former.

5. In a floor cleaner of portable type, the combination of carrying means, mopping 120

- means carried by the carrying means, a tank also carried by the carrying means, a trough carried by the carrying means, and means for conducting fluid from the tank to said trough, said trough adapted to discharge water in a sheet from one of its edges, said trough being tilttable, and said conducting means being equipped with a valve, in combination with a handle movable relative to the carrying means, and connections between the handle and the trough and valve whereby movement of the valve and trough will attend movement of the handle.
6. In a floor cleaner, carrying means in the frame of a casing body having a tank in its rear portion and also having a forward portion open at its bottom, wheels supporting said carrying means, rollers mounted in the forward portion of the carrying means or casing body, a mopping cloth or belt passed around said rollers, means to drive the mopping cloth or belt, means to express water from the cloth or belt, a trough in the upper portion of the tank, a chute arranged to receive water expressed from the cloth or belt and convey the same to said trough, a front wall partially closing the front side of the forward portion of the casing body, a trough carried by said wall, and means to conduct liquid from the tank to said trough.
7. In a floor cleaner, carrying means in the frame of a casing body having a tank in its rear portion and also having a forward portion open at its bottom, wheels supporting said carrying means, rollers mounted in the forward portion of the carrying means or casing body, a mopping cloth or belt passed around said rollers, means to drive the mopping cloth or belt, means to express water from the cloth or belt, a trough in the upper portion of the tank, a chute arranged to receive water expressed from the cloth or belt and convey the same to said trough, a front wall partially closing the front side of the forward portion of the casing body, a trough carried by said wall, and means to conduct liquid from the tank to said trough; the said means being siphonic and being provided with a valve.
8. In a floor cleaner, carrying means in the frame of a casing body, having a tank in its rear portion and also having a forward portion open at its bottom, wheels supporting said carrying means, rollers mounted in the forward portion of the carrying means or casing body, a mopping cloth or belt passed around said rollers, means to drive the mopping cloth or belt, means to express water from the cloth or belt, a trough in the upper
- portion of the tank, a chute arranged to receive water expressed from the cloth or belt and convey the same to said trough, a front wall partially closing the front side of the forward portion of the casing body, a trough carried by said wall, and means to conduct liquid from the tank to said trough; the said means being siphonic and being provided with a valve, and the said trough being tilttable, and the valve and trough being connected with and movable by a handle mounted on and movable relative to the casing body.
9. In a portable floor cleaner, the combination of a casing body having a tank and also having a forward portion open at its underside, a mopping cloth or belt in the forward portion of the casing body, wheels supporting said body, a front wall partially closing the forward side of the casing body and having forwardly deflected arms, a tilttable trough mounted in said arms and having an upstanding projection, a conduit between the tank and said trough to supply the latter, a valve in said conduit, a handle movable relative to the casing body, and means connecting the trough and the valve with the said handle whereby movement of the trough and valve will attend movement of the handle.
10. In a floor cleaner, the combination of carrying means, a tank carried by said means, a mopping cloth or belt also carried by the carrying means, a trough carried by the carrying means, means to conduct fluid from the tank to the trough, means to drive the cloth or belt, and a skirt of flexible sheet rubber connected to and depending from the forward edge of the trough.
11. A floor cleaning machine including a casing having a receptacle in the rear end thereof, said receptacle having a dirt receiving opening in the top portion, a dirt receiving trough mounted in the receptacle below said dirt receiving opening, cleaning means adapted for positioning within the forward portion of the casing and removably secured therein, said cleaning means having means cooperating with the receptacle and positioned over the dirt receiving opening for discharging the dirt picked up thereby through said opening and into the dirt trough, and means carried by said casing and adapted for connection with the cleaning means mounted therein for transmitting power thereto to operate said cleaning means.

In testimony whereof, I affix my signature.

JOHN B. MORTON, JR.
